CHAIN SAW LINK

Edwin T. Dunnington, Indianapolis, Ind.

Application June 3, 1952, Serial No. 291,446

4 Claims. (Cl. 143—135)

1

This invention relates to chain saws and more particularly to means for increasing the effective life of the saw.

As commonly constructed, the chain of a chain saw comprises side plates which interconnect, or form parts of means interconnecting, adjacent teeth-bearing links of the chain and which bear on the face of a cutter bar to transmit thereto the thrusts resulting from reaction of the work on the cutting teeth. In some classes of work, notably situations in which the chain is used in cutting floating logs and consequently runs in water, the side plates develop a tendency to crack at the pitch holes, thus rendering the side plates incapable of sustaining the longitudinal stresses impressed upon them and causing the chain to break.

It is an object of this invention to overcome or counteract this tendency of side plates to split under certain conditions encountered in chain saw operation.

I believe that the above noted tendency of side plates to split arises from work-hardening of those portions of the side plates through which lateral thrust is transmitted to the cutter bar. It seems possible that as a result of such work-hardening the hardened portions of the links possess a different coefficient of thermal expansion from that of other portions of the side plates; and that the cracks develop as a result of differential expansion when the temperature of the side plates increases due to the friction to which they are subjected. In any event, I find that the development of cracks to an extent sufficient to cause side-plate failure can be prevented by interrupting the longitudinal continuity of the side-plate faces which bear on the cutter bar or by so constructing the side plates that any cracks which do develop at their bearing faces are prevented from reaching the pitch holes receiving the pins by which adjacent links of the chain are interconnected.

The accompanying drawing illustrates the invention:

Fig. 1 is a fragmental longitudinal section through the cutter bar of the chain saw, showing a portion of the chain in operative association therewith;

Fig. 2 is an elevational view, on an enlarged scale, of a side plate of the type embodied in the chain of Fig. 1;

Fig. 3 is an elevation of a modified form of side plate;

Fig. 4 is a view similar to Figs. 2 and 3 illustrating a further modification.

As indicated in Fig. 1, a chain saw commonly

2

includes teeth-bearing links 10 interconnected by other links at least some of which include side plates 11. In operation, the chain runs along one face of a cutter bar 12, such face being provided with a groove 13 which slidably receives tongues 14 on certain of the chain links. The remaining links of the chain embody the side plates 11 previously referred to, which side plates bear on the cutter-bar face at the sides of the groove 13 and transmit to the cutter bar the lateral thrusts imposed on the chain by the work.

Each side plate 11 is formed at each end to provide an extended bearing face 15 engageable with the cutter bar to transmit the thrusts previously mentioned. As noted, cracks developing at the surfaces 15 due to conditions encountered in use tend to extend themselves until they reach the pitch holes 16 receiving the pins 17 through which adjacent chain links are interconnected. When a crack occurs and extends itself to meet a pin hole, the side plate is greatly weakened and will eventually fail, causing a breaking of the chain.

In the side plate shown in Fig. 2, I have interrupted the continuity of each bearing face by providing it, opposite each associated pitch hole 16, with a notch 17. Such a notch serves to reduce the extent, longitudinally of the chain, of those side-plate portions which would be subjected to internal strain as the result of differential thermal expansion. As a result, the notches tend to prevent, and are found in practice to be effective in preventing, the start of cracks in the side plates.

In the modified form of side plates shown in Fig. 3, the plate is provided inwardly from the bearing surface 15 with a slot 18 which, longitudinally of the side plate, is substantially co-extensive with the adjacent pitch-hole 16. In fact, the length of the slot 18 may be slightly greater than the diameter of the pitch hole. With the slots 18 present in the side plate, any crack which develops at a bearing face 15 is prevented from extending itself to reach the pitch hole. Such a crack, once started, may extend itself inwardly of the link; but when it reaches the slot 18, further extension is prevented.

In the arrangement illustrated in Fig. 4, the side plate embodies both the features illustrated in Figs. 2 and 3. The side plate shown in Fig. 4 is provided opposite each pitch hole with a T-shaped slot 10. The shank or transversely extending portion of each such T-shaped slot opens into the bearing face 15 and corresponds to the notch 17 in the side plate shown in Fig. 2 while the remaining slot-portion, extending longi-

tudinally of the side plate 11, corresponds to the slot 18 of Fig. 3. The slot of Fig. 4 both inhibits the initial development of cracks and also prevents any cracks which do develop from extending themselves until they reach the pitch holes 16.

Chain saws incorporating chains of the type illustrated in Figs. 2, 3, and 4 have been found to be much less subject to side-plate failure, and hence possess a materially longer life, than chain saws in which the side plates are not modified by the presence of notches or slots, 17, 18, or 19.

I claim as my invention:

1. In a chain saw having a chain including links each comprising a pair of side plates provided adjacent their ends with aligned holes receiving transverse pins pivotally connecting said side plates to adjacent chain links; a cutter bar, said side plates having at their edges opposite said holes bearing faces engaging said cutter bar, each side plate having between each hole and the adjacent bearing face an opening spaced from such hole.

15

2. The invention set forth in claim 1 with the addition that said opening opens into the adjacent bearing face to interrupt the longitudinal continuity thereof.
3. The invention set forth in claim 1 with the addition that said opening is spaced inwardly from the bearing face and is substantially longitudinally coextensive with the hole.
4. The invention set forth in claim 1 with the addition that each of said openings is T-shaped, having a transversely extending portion opening into the bearing face and a longitudinally extending portion spaced inwardly from the bearing face.

EDWIN T. DUNNINGTON.
